UNITED STATES PATENT OFFICE.

WILLIAM ADRON RAGSDALE, OF WASHINGTON, DISTRICT OF COLUMBIA,
ASSIGNOR TO INTERNATIONAL COTTON SEED DELINTING COMPANY,
OF WASHINGTON, DISTRICT OF COLUMBIA. A CORPORATION OF MAINE.

COTTON-SEED-DELINTING MACHINE.

No. 821,256.

Specification of Letters Patent.

Patented May 22, 1906.

Application filed November 17, 1905. Serial No. 287,812.

To all whom it may concern:

Be it known that I, WILLIAM ADRON RAGSDALE, a citizen of the United States, residing at Washington, in the District of Columbia, have invented certain new and useful Improvements in Cotton-Seed-Delinting Machines, of which the following is a specification.

This invention relates to the art of delinting cotton-seed, and has special reference to an improved and practical construction of delinting-machine comprising positive and effectual means for thoroughly removing the lint from cotton-seed and effecting the complete separation therefrom of the fiber, dust, trash, and other foreign matter.

In the practical operation of cotton-seed-oil mills the preparation of the seed for the press is a step in the process which is of the utmost importance. It is therefore the constant aim of oil-mill operators to clean the cotton-seed as thoroughly as possible of the lint adhering thereto. Various expedients have been resorted to for accomplishing this purpose, for the reason that heretofore it has been found practically impossible to provide in a single delinting-machine the construction and capacity necessary to accomplish a thorough delinting of the seed. Consequently one of the important parts of the present-day cotton-seed-oil mill is the "linter-machine," through which the cotton-seed received from the gin is run for the purpose of removing therefrom the long fiber and also as much of the other fiber as possible through the aid of such a machine. This operation is entirely independent of what is understood to be the delinting of cotton-seed, and in this connection it is to be noted that the primary and fundamental object of the present invention is to consolidate in a single machine co-operating mechanisms which simultaneously provide for the "lintering" and "delinting" of the cotton-seed in the sense understood by the oil-mill operators.

In carrying out the foregoing object of consolidating co-operating linting and delinting mechanisms in a single machine the invention provides an improved construction wherein the long lint or fiber is effectually removed from the cotton-seed simultaneously with the delinting action which scours off the short fiber and which short fiber, together

with the dust, trash, and other foreign matter, is disposed of through a suction discharging action entirely independent of the discharging means provided for the long lint. 55

Another and important object of the invention is to provide improved and effectual means for supplying air uniformly throughout the delinting-chamber in such a way as to positively insure the drawing off of the short lint, dust, trash, and foreign substance without interference with that portion of the mechanism which takes out and disposes of 60 the long lint or fiber.

With these and other objects in view, which will more readily appear as the nature of the invention is better understood, the same consists in the novel construction, combination, and arrangement of parts hereinafter more fully described, illustrated, and claimed. 70

The essential features of the invention involved in carrying out the objects above indicated are susceptible to structural change without departing from the scope thereof; but a preferred embodiment of the machine is shown in the accompanying drawings, in which— 75

Figure 1 is a side elevation of a cotton-seed-delinting machine embodying the present invention. Fig. 2 is a vertical longitudinal sectional view of the complete machine. Fig. 3 is a cross-sectional view on the line 3-3 of Fig. 85 2. Fig. 4 is an enlarged sectional view of a fragment of the rotary agitator, which also serves the function of an air-distributer for feeding air into and throughout the delinting-chamber of the scouring-shell. 90

Like references designate corresponding parts in the several figures of the drawings.

In carrying out the present invention the delinting mechanism proper or that part of the machine which provides for scouring off 95 the closely-adhering short lint or fiber is housed within the outer case 1, preferably of a cylindrical form and essentially consisting of an imperforate cylindrical body supported between the open and oppositely-arranged end heads 2 and 3, which also constitute stands for properly supporting the entire machine. Also the end heads 2 and 3 constitute closures for the ends of the interior cylindrical scouring-shell 2^a, which is 100 arranged inside of the outer case. The latter

is arranged in concentric spaced relation to the scouring-shell 2^a therein to provide a suction-chamber which nearly completely envelops the scouring-shell, and at one side 5 (preferably at the bottom) the said outer case is formed with the downwardly-convergent hood portions 3^a, the side and end walls of which converge to a central outlet-neck 4. This outlet-neck has connected therewith 10 one end of an air-suction pipe 5, leading to the inlet of a suitable exhaust or suction fan 6. The latter provides for maintaining a suction of sufficient intensity to draw out and discharge from the scouring-shell 2 short fiber 15 or lint, trash, and other foreign matter worked from the seed within the working space 7, which is provided between the inner surface of the scouring-shell 2^a and the periphery of the rotary agitator 8, hereinafter more fully 20 referred to. Furthermore, the hood portion of the outer case or suction-chamber is provided in one side thereof with an auxiliary air-inlet 9, designed to be covered and un-covered by the regulating damper or gate 25 10. This damper or gate 10 may be manipulated to increase or diminish the suction at will, thus placing under the control of the operator a simple means for regulating the entire delinting action and the rapidity of discharge of the delinted seed.

The scouring-shell 2^a within the outer suction-case is of a general cylindrical shape and arranged to extend longitudinally within the case from end to end. (See Fig. 2.) The 35 said shell is of a sectional construction and essentially consists of a series of parallel circular holders 11 and abrasive rings 12, carried by said holders, whereby the series of abrasive rings will provide an interior abrasive scouring-surface against which the seed is worked by the agitator 8. The entire series of circular holders 11 and the abrasive elements carried thereby form the main cylindrical body of the scouring-shell and are 40 arranged side by side in regular spaced relation to leave therebetween the intervening annular discharge-slits 13 in communication with the interior working space 7. These slits 13 are also in communication with the 45 suction-chamber enveloping the scouring-shell, whereby short fiber and other trash worked from the seed can readily escape into the suction-case and thence be drawn out of the same through the suction discharge-pipe 5.

55 A feature of practical importance in connection with the construction of the slotted or perforated scouring-shell is the fact that the circular holding-rings 11 for the abrasive rings 12 are triangular in cross-section, there- 60 by providing between contiguous rings outwardly-flaring annular clearance-spaces 14 in communication with the slits 13 and forming flaring discharging openings or exits for the lint and trash, some of which is drawn out by 65 the suction action, while the long lint is taken

out of the scouring-shell and disposed of through the medium of the coöperating linting mechanism to be presently referred to. By reason of the construction specified—namely, the provision of narrow intervening 70 annular discharge-slits opening into flaring annular spaces between the rings—it is obvious that a perfectly free discharge is secured at all times for the lint and trash and choking of such discharge is obviated. Furthermore, on account of the flaring spaces 14 a uniform and strong suction can be maintained about the scouring-shell at the points or slits where the short lint and trash leave the working space 7.

Any desired number of the holding-rings 11 for the abrasive elements may be utilized, and these holders are individually formed with an inner peripheral groove 15, receiving a correspondingly-shaped retaining-tongue 16, formed on the outer portion of the abrasive ring 12. This construction is a practical one from the fact that it provides a tight wedging fit for the abrasive rings in the holders therefor.

The abrasive rings 12 are formed of carborundum, emery stone, or equivalent abrasive substance to provide an inner abrasive scouring-surface for the shell, and to provide for the convenient and proper support of the 95 several holders each of the same may be provided at diametrically opposite sides with the hanger-hooks 17, adapted to engage over and rest upon the side supporting-bars 18, arranged longitudinally of the machine with-in opposite side portions of the outer case 1. In addition to the said hooks and bars 17 and 18, respectively, each holder is provided at the lower side thereof with a bifurcated keeper-lug 19, engaging over a longitudinally-100 arranged support bar 20. This construction securely and accurately positions and supports the various holders and their abrasive rings and also permits the same to be readily removed and replaced.

A feature of great importance in this invention is the specific construction of the rotary agitator 8, whereby said agitator not only provides for keeping the seed in agitation and pressing the same against the inner 115 scouring-surface of the shell 2, but also acts in the capacity of an air-distributer for uniformly feeding air into and distributing it throughout the working space 7. This agitator essentially comprises a cylindrical hollow air-drum 21 of a length coextensive with that of the abrasive scouring-shell 2 and mounted upon a longitudinal drive-shaft 22, whose ends are journaled in suitable bearings 23 and carried upon the end heads or castings 120 2 and 3, said drive-shaft being driven from any suitable source of power. In the practical construction of the machine the hollow air-drum 21 is preferably made up of a number of axially-aligned cylindrical shell-sections 125 130

24, provided throughout their entire extent longitudinally and circumferentially with a multiplicity of air-feeding perforations or ports 25 and held supported in properly aligned relation upon a plurality of supporting-spiders 26, secured fast to the drive-shaft 22 at suitably-spaced intervals. It will be observed that each of the supporting-spiders 26 is of an open-spoked formation to permit the free passage of air therethrough and is provided with a central hood portion 27, fitting the drive-shaft, and with a double-flanged rim portion 28, projecting from both sides of the plane of the spokes, upon which rim portions are fitted the ends of the perforate shell-sections 24 of the drum-body. It will be noted by reference to Fig. 4 of the drawings that the contiguous ends of the adjacent shell-sections 24 fit over and rest upon the opposite rim-flanges 28 of the same supporting-spider 26. Also the terminal spiders 26—namely, those disposed at the extreme ends of the agitator 8—are each arranged to have the outer rim-flanges 28 thereof rotatably register in the air-inlet eyes 29, provided in the end heads or castings 2 and 3. This construction is plainly shown in Fig. 4 of the drawings and provides not only for an extra end-bearing support for the ends of the air-drum or agitator, but also serves to close in the ends of the working space 7, while at the same time freely admitting an unlimited and ample supply of air into the perforated air-drum from both ends thereof.

35 In addition to being so constructed as to provide supporting means for the several perforated sections 24 of the air-drum the supporting-spiders 26 are provided with a plurality of fastening-lugs 30, projecting radially and centrally from the rim portions thereof and arranged at intervals on said rim portions to provide holding members or supports for the longitudinally-arranged pressure blades or wings 31. These pressure blades 45 or wings 31 are arranged on the outer side of the drum-body 21 and are fastened directly to the projecting fastening-lugs 30 by means of the belts 32 or equivalent fastening devices, which provide simple and practical 50 means for holding the blades in place, as well as permitting the ready and convenient removal thereof for purposes of repair. The said pressure-blades 31 constitute a part of the rotary agitator and air-distributer, and 55 the same are preferably constructed of flat strips of steel or equivalent metal and are non-resilient. Also the said blades or wings are arranged in any suitable number upon the drum-body and are of a width nearly 60 equaling the width of the working space 7, so as to operate in close proximity to the abrasive working face of the scouring-surface. An effective feature of the rigid pressure-blades 31 is that the same are of a saw-tooth construction—that is, provided along their outer

working edges with a continuous series of angular working teeth 33, which provide alternating points and notches, as plainly shown in Figs. 2 and 4 of the drawings. The best results have been attained by arranging the 70 rigid toothed blades or wings 31 in regular longitudinal rows extending from end to end of the drum-body, and by reason of projecting radially and centrally from the drum-body the same will be rotated so as to present their flat sides to the seed.

In action the pressure-blades act, primarily, in the capacity of what may be termed "non-abrasive" members to press the seed in firm contact with the inner abrasive surface of the 80 scouring-cylinder, and while the points of the toothed edges of the blades serve to move the seed against the scouring-surface it will be obvious that the seed will freely roll in and out of the notches of the toothed edges. 85 Hence the seed will be prevented from cracking or mashing, while at the same time being held up to the abrasive elements, thus insuring a very effective delinting action, which removes the closely-adhering short lint, while 90 the long lint or fiber is taken care of by the co-operating linting mechanism now to be referred to.

In order to secure a proper delinting action, it is absolutely necessary to take care of and 95 dispose of the long fiber or lint in addition to the means provided for removing and disposing of the short lint or fiber, which more closely adheres to the body of the cotton-seed. The present invention proposes to secure this desirable and practical result as a 100 part of the delinting operation itself through the employment of a linting mechanism co-operating directly with the short fiber or delinting mechanism. What has been termed 105 the "lint" mechanism for accomplishing this result essentially consists of a separating saw-cylinder 34 and a discharging-brush 35. The saw-cylinder 34 comprises a cylinder or 110 gang of circular separating-saws 36, arranged and mounted in substantially the same manner as ordinary gin-saws, the same being spaced in parallel relation and mounted upon a common saw-arbor 37, driven by any suitable belt or gear connection at a proper speed. 115 In adapting the gang or cylinder of saws 36 to the other parts of the machine it will be observed that the intervals or spaces between the individual or separate saws correspond to the spacing of the abrasive rings forming the 120 scouring-shell, so that the saw-arbor 37 may be supported in such a position as to permit the individual saws to project into and through the discharging slits or intervals 13 between the abrasive rings of the scouring-shell. The edges of the saws entering the slits 13 are held out of contact with the contiguous portions of the adjacent abrasive rings, while at the same time projecting past the inner scouring-surface of the shell, so that 125 130

the teeth of the saw will operate directly in the working space 7, and thereby serve to catch and take out of the said working space the long fiber which is always carried by the 5 seed coming from the cotton-gin.

It is preferable in carrying out the invention to arrange the gang or cylinder of saws 36 above the scouring-shell, and to provide for properly housing the saws the end heads 10 or castings 2 and 3 support therebetween a closed saw-chamber 38, surmounting the outer suction-case, and preferably provided at one side with a normally closed door 39, permitting ready access to the said saw-chamber. The suction-chamber within the case 1 is cut off from the interior of the saw-chamber 38 by the cut-off partitions 40, extending across the suction-chamber between the wall of the case 1 and the outer side of the 15 scouring-shell 2^a at the point of juncture between the case 1 and the chamber 38. This construction prevents the strong draft from the pipe 6 for carrying out the short lint and dust from interfering with the action of the 20 saws and the fan action of the discharging-brush 35, which is arranged within a brush-casing 41, arranged at one side of the saw-chamber, but likewise conveniently mounted between the heads or castings 2 and 3. The 25 rotating brush 35 is mounted on a brush shaft or arbor 42, driven by any suitable belting or gearing, and the said brush operates against the saws at one side of the saw-cylinder in the same manner as the brush of a gin; 30 but in the present invention at the point of communication between the saw-chamber 38 and the brush-casing 41, there is arranged a draft-cut-off screen made up of a plurality of saw-ribs 43, arranged between the individual 35 saws contiguous to the brush-engaged edges thereof. Said ribs 43 do not interfere with the lint being carried past the same by the saws, but at the same time cut off the draft sufficiently from the suction connections 40 with the scouring-shell so as to not interfere with the fan action of the brush 35 in sweeping the lint from the saws and blowing the same through the lint-discharging flue 44 onto the condenser 45. The arrangement of 45 the lint-discharging flue 44 to the brush 35 and to the condenser 45 is the same as is common to gin constructions, as is well understood by those skilled in the art.

At one end the machine is provided with a 50 feed-spout 46 for admitting undelinted material as it comes from the gin into the scouring-shell, and at the opposite end the shell is in communication with a delivery-spout 47 for the delinted seed. The fiber which is 55 taken out from the scouring-shell by the saws is deposited on and taken care of by the condenser as a separate commercial product of the machine.

From the foregoing it is thought that the 60 construction, operation, and many advan-

tages of the herein-described machine, will be readily apparent without further description, and it will be understood that various changes in the form, proportion, and minor details of construction may be resorted to 70 without departing from the spirit or sacrificing any of the advantages of the invention.

Having thus described my invention, what is claimed, and desired to be secured by Letters Patent, is—

1. In a cotton-seed-delinting machine, a 75 scouring-shell having a perforate body portion, suction discharging means for maintaining a draft through said body portion, an agitator within the shell, and means for admitting air into the shell through the center thereof and circulating the same from the center outward through the perforate body portion of the shell.

2. In a delinting-machine, a cylindrical 80 scouring-shell consisting of a series of spaced abrasive rings, an agitator within the shell, suction discharging means including an outer suction-case arranged about the shell, a closed saw-chamber disposed at one side of 85 the suction-case, a brush-casing arranged at one side of the saw-chamber and in communication therewith, a ribbed draft-cut-off screen located between the brush-casing and the saw-chamber, a cylinder of rotary circular saws mounted within the saw-chamber and projecting into the shell through the spaces between the rings thereof, said saws also extending through said draft-cut-off screen, and a rotary discharging-brush arranged within the brush-casing and operating 90 against the saws.

3. In a delinting-machine, a scouring-shell having a perforate body portion, an agitator within the shell, means for admitting air into 105 the shell through the center thereof, suction discharging means including an outer suction-case arranged about the shell, and rotary circular separating-saws projecting into the shell through the perforate body portion 110 thereof.

4. In a delinting-machine, an abrasive scouring-shell having a perforate body portion, a combined agitator and air-feeding distributor arranged within the shell, suction 115 discharging means for removing short fiber and trash from the perforate body portion, and separating-saws projecting into the shell through said perforate body portion.

5. In a delinting-machine, an outer case, a 120 scouring-shell having an inner abrasive surface and a series of annular flaring spaces opening at their apices into the shell, an agitator, and circular rotating saws projecting into the shell through said flaring spaces.

6. In a delinting-machine, a cylindrical 125 scouring-shell comprising a continuous series of cross-sectionally triangular abrasive rings spaced apart to leave intervening discharge-slits, suction discharging means for maintain- 130

ing a suction through said slits, separating-saws projecting into the shell through said slits, and an agitator working in said shell.

7. In a delinting-machine, a scouring-shell having a perforate body portion, suction discharging means for maintaining a draft through the perforate body portion, and a combined rotary agitator and air-distributer arranged within the shell and having a hollow perforate body portion in communication with the outer air.

8. In a delinting-machine, a scouring-shell, and a combined rotary agitator and air-distributer working in the shell and having a hollow perforate body portion in communication with the outer air.

9. In a delinting-machine, a scouring-shell, and a combined rotary agitator and distributor operating within the shell and having a perforate body portion, and a plurality of rigid pressure-blades projecting through said body portion.

10. In a delinting-machine, a scouring-shell, and a combined rotary agitator and dis-

tributer operating within the shell and having a perforate body portion, and a plurality of rigid pressure-blades projecting through said body portion, said pressure-blades having saw-tooth working edges.

11. In a delinting-machine, a scouring-shell, and a combined rotary agitator and air-distributer consisting of a shaft, a plurality of spaced spiders mounted on the shaft and having double-flanged rim portions and radial fastening-lugs, a hollow air-drum made up of a plurality of axially-aligned perforate shell-sections fitted on the rim portions of the spiders, and pressure-blades arranged on the drum and secured to said fastening-lugs, the said air-drum having communication at its ends with the outer air.

In testimony whereof I affix my signature in presence of two witnesses.

WILLIAM ADRON RAGSDALE.
